ABRAHAM LEVINE, OF ELIZABETH, NEW JERSEY, AND OSSIP J. WALINSKY, OF NEW YORK, N. Y.

PIVOTAL GARMENT-SUPPORTING DEVICE

Application filed October 3, 1928. Serial No. 309,927.

Our present invention relates generally to supporting devices, and has particular reference to a pivotal garment-supporting device designed primarily for use in connection with the wall of a suitcase, trunk, or the like.

Although we have herein illustrated and shall hereinafter describe our invention as applied specifically to the wall of a suitcase, nevertheless it will be understood that as to certain phases of our invention it is not limited to such an employment.

One of the objects of our invention is to provide a garment-supporting device in the nature of a rung or the like, which rung is mounted with respect to the suitcase wall in a manner whereby the rung may be moved toward and away from said wall. In this way, access to the rung is facilitated when garments are to be applied or withdrawn therefrom, and at the same time the rung is adapted to be moved into a normal position in close proximity to the wall for purposes of allowing the packed suitcase to be closed with the garment or garments efficiently supported therein.

More particularly, it is an object to provide a rung in combination with means for so mounting it as to permit reciprocation of the rung parallel to itself and parallel to the wall toward and away from the latter.

A more specific object of our invention lies in providing an efficient yet simple and compact mounting means composed of a minimum of elements adapted to cooperate in a simple and staunch manner and designed to occupy a minimum amount of space.

Another object of our invention lies in providing means for permitting the rung to be locked in a removable manner in relatively close proximity to the wall, thereby assuring the neat and efficient accommodation and packing of a supported garment within the suitcase.

An important object of our invention lies in providing a pivotal mounting for the rung whereby the latter may be swung back and forth about one end thereof, in this way facilitating the accessibility thereto for purposes of applying or removing garments.

Another object lies in providing a sup-

porting device whereby and wherein the rung is simultaneously capable of the two types of movement heretofore mentioned. More particularly, our device permits translational movement of the rung bodily toward and away from the wall and it also permits pivotal movement of the rung about one end thereof, said pivotal movement being possible during all translational proximities of the rung with respect to the wall.

Briefly, our invention resides in the provision of a pair of juxtaposed brackets pivoted at spaced portions of the wall, the rung being supported in a particular manner between these brackets. Between one end of the rung and the corresponding bracket we provide a pivotal mounting to permit the rung to be swung around this end. To permit such swinging to be effected, we provide means at the opposite end of the rung for permitting removable association thereof with the corresponding opposite bracket.

A particular feature of our invention lies in the provision of mechanism in association with said pivotal mounting for permitting association and disassociation of the pivoted rung end, and for preventing such association or disassociation except after the rung has been swung through and beyond a predetermined angularity.

For the attainment of the foregoing objects and such other objects as may hereinafter appear or be pointed out, we have illustrated one form of our invention in the accompanying drawings in which—

Figure 1 is a front elevational view of a garment-supporting device of the present character associated with the wall of a suitcase and shown in normal position;

Figure 2 is a cross-sectional view taken substantially along the line 2—2 of Figure 1;

Figure 3 is a cross-sectional view taken substantially along the line 3—3 of Figure 2;

Figure 4 is a cross-sectional view taken substantially along the line 4—4 of Figure 2;

Figure 5 is a view similar to Figure 2 showing the supporting device in its extreme outward position;

Figure 6 is a cross-sectional view taken substantially along the line 6—6 of Figure 1;

Figure 7 is a cross-sectional view taken substantially along the line 7—7 of Figure 6;

Figure 8 is a plan view of the parts shown in Figure 7, the dot and dash lines showing the rung in one of its possible positions; and

Figure 9 is a perspective view of a portion of some of the elements shown in Figures 7 and 8.

We have shown a garment-supporting device of the present character in association with a wall 10 comprising the peripheral flanges 11, 12, and 13. A rung 14 extends between the flanges 11 and 13 and is normally substantially parallel to the wall 10. It is provided at one end with a ferrule 15 or the like, the latter having a laterally projecting pin to facilitate the mounting of that end of the rung; and the rung is provided at its opposite end with a ferrule 16 or the like, the latter being provided with tabs and pivots of particular construction to be described in greater detail hereinafter.

A pair of substantially similar brackets are pivotally associated with the wall portions 11 and 13 respectively and are adapted to support the rung 14 therebetween. As to those portions of these brackets which are identical, a description of one will be sufficient.

Each bracket comprises the four mutually pivoted links 17, 18, 19, and 20 which define a parallelogram. The link 17 is rigidly associated with the flange 11 as by means of rivets 21 and 22. The links 18 and 19 are of substantially equal length and form opposite parallel sides of the parallelogram. They are pivoted at the ends 23 and 24 to the link 17, and between the opposite ends of the links 18 and 19 is the relatively short link 20.

The corresponding bracket on the flange 13 is symmetrically constructed and differs from the left-hand bracket in the particular construction of the top link member corresponding to the link 20.

Thus, whereas the link 20 is provided with the resilient upwardly extending tongue 25 provided with an aperture adapted to receive the pin of the ferrule 15, the corresponding link member of the right-hand bracket is constructed in the manner more fully disclosed in Figures 7, 8, and 9.

Referring particularly to Figure 9, we provide a pair of superposed shelves 26 and 27, these shelves being provided with apertures 28 and 29 respectively, these apertures being in alignment with one another and serving as pivot bearings for pivots presently to be described. An upward extension 30 is provided with a struck-up portion or abutment 31 which extends in the direction of the shelves 26 and 27 and which is in substantial alignment with the apertures 28 and 29.

In Figure 7 we have shown the ferrule 16 provided with two superposed lateral extensions 32 and 33, the latter being provided

with aligned downwardly extending pivots 34 and 35 respectively. These pivots are adapted to enter the apertures 29 and 28 respectively as shown most clearly in Figure 7.

The extension 33 is provided with a tab 36 of sufficient length to engage beneath the abutment 31 during certain positional adjustments of the rung 14. More particularly upon referring to Figure 8, it will be noted that the tab 36 engages beneath the abutment 31 as long as the rung 14 is in any position between the normal full-line position of Figure 8 and the outwardly swung dot and dash line position of this figure.

It will thus be seen that the rung 14 is removably supported between the two brackets. Under normal circumstances the rung is substantially parallel to the wall 10 as shown in Figure 1. If it is desired to pivot the rung 14 around its right-hand end, the resilient extension 25 is manipulated to release the ferrule 15. The rung is then free to swing around the pivotal mounting disclosed in Figures 7-9 so as to render access to the rung relatively simple. It is to be noted that the rung is irremovable with respect to the right-hand bracket so long as it swings within a predetermined arc. This facilitates the pivoting under normal requirements and prevents annoyance by a possible disengagement of the right-hand end of the rung. On the other hand, if total removal of the rung is desired, it is only necessary to swing the rung through and beyond the arc shown in Figure 8, at which time the tab 36 will release itself from beneath the abutment 31 to permit the pivots 35 and 34 to be drawn upwardly out of the pivot bearings 28 and 29. Reassociation of the rung with the right-hand bracket is accomplished in the same manner, the rung being first positioned at an angularity at least equal to that indicated by dot and dash lines in Figure 8.

One feature of our invention lies in providing means for moving the pivotal mounting of Figures 7-9 bodily to and from the wall 10 without destroying the parallelism of the pivot axis with respect to the wall 10. This is accomplished by means of the brackets hereinbefore described.

In Figure 2 the left-hand bracket is shown in its normal position, the parallelogram formed by the links thereof being in the nature of a rectangle. In Figure 5 the links have been adjusted so as to define a rhomboid. It is to be noted that the link 20 is in the same horizontal position throughout the entire adjustment of this bracket.

The same is true with respect to the corresponding pivotal mounting associated with the other bracket as seen most clearly in Figure 6. The pivot axis, substantially vertical as viewed in Figure 6, remains parallel to itself throughout the full adjustment of this bracket from the full-line position to the ex-

tended position shown in dot and dash lines.

A strut 37 extends between the links 19 and 19' and constrains the two brackets to move in unison. In this way, the rung 14 may be bodily moved in a translational manner toward and away from the wall 10. Thus, without withdrawing either end of the rung 14 from association with its corresponding bracket, the rung may be rendered accessible

10 for many purposes by simply drawing the same outwardly with respect to the wall 10.

To limit the outward movement we provide abutments which are herein illustrated as constituted of the rivets 22 and 22'. These rivets are purposely offset as shown most clearly in Figures 2, 5, and 6 so as to be encountered by the opposite ends of the strut 37 after a predetermined outward swinging of the brackets.

20 To enhance the efficiency of our device, we provide means for yieldably locking the rung in the normal position shown in Figure 1. In the illustrated embodiment, we have shown a rounded projection 38 provided on the link

25 member 17, this projection being so positioned as to be encountered by an aperture 39 provided in the link 19. The link 19 is somewhat resilient and the aperture 39 is purposely of smaller diameter than the outermost 30 diameter of the projection 38. As a result, the link 39 will snap into a yieldably locked position as shown in Figure 2 whenever the parts are brought into the positional relationships shown in this figure. A corresponding

35 interengagement between two similar complementary latching members is provided in association with the opposite bracket.

It will thus be seen that we have provided a device extremely simple in structural nature

40 yet highly efficient in operation. The rung 14, serving as an efficient garment-supporting device is so mounted as to be capable of movement both toward and away from the wall 10 in a translational manner, and pivotally with 45 respect to said wall about one end thereof. Further, the rung 14 is so pivotal regardless of its translational proximity to the wall 10. Further, the rung 14 is totally removable with great facility when such removal is de-

50 sired.

We do not mean to limit ourselves to the particular details of construction herein illustrated and described. For example, although we have employed the rivets 22 and 55 22' as abutments, it is obvious that any suitable abutment arrangement may be employed. Also, we have shown a pivotal mounting of particular structure in Figures 7-9, but it will be obvious that such pivotal

60 mounting may be modified in a variety of ways without departing from the basic structural nature and purpose thereof.

In general, it will be obvious that changes in the details herein described and illustrated 65 for the purpose of explaining the nature

of our invention may be made by those skilled in the art without departing from the spirit and scope of the invention as expressed in the appended claims. It is therefore intended that these details be interpreted as illustrative, and not in a limiting sense.

Having thus described our invention and illustrated its use, what we claim as new and desire to secure by Letters Patent is—

1. In combination with the wall of a suitcase or the like, a garment-supporting device comprising a rung, and means for mounting the rung for translational movement toward and away from said wall about a horizontal axis and also for pivotal movement about one end thereof about a vertical axis.

2. In combination with the wall of a suitcase or the like, a garment-supporting device comprising a rung, means for mounting the rung for movement parallel to itself and to said wall toward and away from the latter, said means comprising a pair of bracket members arranged to move in unison and pivoted to spaced portions of the wall, and means for removably supporting the rung between said bracket members, said last-named means including mechanism for removably associating one end of the rung with the corresponding bracket member to permit pivotal movement of the rung, said mechanism preventing association or disassociation of said end except when the rung is positioned or swung to a predetermined angularity with said wall.

3. In combination with the wall of a suitcase or the like, a garment-supporting device comprising a rung, means for mounting the rung for movement parallel to itself and to said wall toward and away from the latter, said means comprising a pair of bracket members arranged to move in unison and pivoted to spaced portions of the wall, and means for removably supporting the rung between said bracket members, said last-named means including mechanism for removably associating one end of the rung with the corresponding bracket member to permit pivotal movement of the rung, said mechanism preventing association or disassociation of said end except when the rung is positioned or swung to a predetermined angularity with said wall, and said mechanism comprising a tab carried by said rung end and means carried by said bracket member for engaging said tab as long as said angularity is less than said predetermined amount.

4. In combination with the wall of a suitcase or the like, a garment-supporting device comprising a rung, a pivotal mounting for one end of the rung and whose pivot axis is substantially parallel to said wall whereby the rung may be swung back and forth about said axis, and means for moving said pivotal mounting bodily toward and away from said

wall without destroying said parallelism, said pivotal mounting including mechanism for removably associating said rung end therewith, and said mechanism preventing 5 association or disassociation of said end except when the rung is swung beyond a predetermined angularity with said wall.

5. In combination with the wall of a suitcase or the like, a garment-supporting device 10 comprising a rung, a pivotal mounting for one end of the rung whereby the latter may be swung back and forth about said end as an axis, and means for moving said pivotal mounting bodily toward and away from said 15 wall, said pivotal mounting including mechanism for removably associating said rung end therewith, and said mechanism preventing association or disassociation of said end except when the rung is swung through and 20 beyond a predetermined arc.

6. In combination with the wall of a suitcase or the like, a garment-supporting device comprising a rung, means for removably mounting the rung for movement parallel to 25 itself and to said wall toward and away from the latter, means for pivoting the rung about one end thereof, and automatically operating means for locking the rung against removal when it is in position parallel to said 30 wall.

7. A garment supporting device for attachment to a suit case or the like comprising a rung, opposed bracket members, means associated with the bracket members for detach- 35 ably receiving opposite ends of the rung, said means comprising a pivotal support on one bracket member for mounting the rung for swinging movement in a horizontal plane about one of its ends and means associated 40 with said pivot for preventing detachment of that end of the rung while the rung is in a position parallel to the plane of the bracket members and means for supporting the bracket members from opposed walls of a suit 45 case or the like for bodily parallel movement toward and away from the interior of the trunk whereby the rung can be first given a translational movement outwardly from the suit case, then a pivotal movement about one 50 end, and then removed altogether.

In witness whereof we have signed this specification this 27th day of September, 1928.
